Patented July 16, 1918.

UNITED STATES PATENT OFFICE.

MILTON L. HELLER, OF BROOKLYN, NEW YORK.

WAISTBAND.

1,272,439.

Specification of Letters Patent. Patented July 16, 1918.

Application filed June 6, 1917. Serial No. 173,220.

To all whom it may concern:

Be it known that I, MILTON L. HELLER, a citizen of the United States, residing at Brooklyn, in the county of Kings and State 5 of New York, have invented certain new and useful Improvements in Waistbands; and I do hereby declare the following to be a full, clear, and exact description of the invention, such as will enable others skilled 10 in the art to which it appertains to make and use the same.

This invention relates to the improvement and construction of waist bands and more particularly to that type used in boys' 15 trousers.

It has for an object to provide a waist band having an elastic webbing secured therein with means for obtaining a number of adjustments to always assure a tight 20 fit of the waist band about the waist of a wearer.

A further object of this invention is the provision of a waist band having an elastic webbing detachably secured therein and 25 having means carried by said waist band and by said elastic webbing to permit a number of adjustments being had.

A further object of this invention is the provision of a waist band which may be 30 manufactured and sold as a stock article for attachment in trousers and the like and having said waist band so formed as to eliminate all other supporting means for the trousers in which this type of waist band is 35 included.

Further objects will be apparent from the following specification, appended claims and drawings, in which,

Figure 1 is a perspective view of a pair 40 of youths' trousers showing this waist band included therein,

Fig. 2 is a perspective view of the waist band detached,

Fig. 3 is a longitudinal horizontal sec- 45 tional view through the waist band,

Fig. 4 is a vertical sectional view showing the waist band secured in a garment,

Fig. 5 is a perspective view of one of the clamps carried at the end of the elastic web- 50 bing showing one face thereof, and

Fig. 6 is a similar view showing the oppo- site face thereof.

With the waist band of this type secured in trousers, it is evident that when worn no 55 other fastening or supporting means are required and that provision is made for ad-

justment of the elastic webbing to accom- modate itself to waists of various measure- ments. The elastic webbing which com- 60 prises the adjustable feature of this type of waist band is removable from the waist band for substitution of other strips of web- 65 bing, or for laundering purposes and the fasteners carried by the end of this elastic webbing are such as to prevent accidental displacement between the webbing comprising the waist band and the garment proper.

Referring to the drawings in which the several parts are clearly shown, 10 indicates 70 a pair of trousers of the type worn by youths, and in this garment, is secured the waist band 11. This waist band comprises a non-elastic webbing having its upper edge folded as at 13 to form a neat seam when stitched to the garment proper. The lower 75 edge of the webbing is attached to the garment as by the row of stitching 15, and the upper edge may be stitched through both plies of the webbing 11 as at 16, or the stitching 80 may pass through the folded portion only. It is understood that this waist band is fastened to the garment in quite the manner as is commonly used and that when the waist band is secured, a tubular pocket is 85 formed between the waist band and the garment.

The webbing 11 has the transverse slits 17 therein which are reinforced as by the button-hole stitching and secured to the underside of the webbing 11 as by the said 90 stitching is a lining 18 which reinforces the webbing 11 from these points to the end thereof.

An elastic webbing 19 is passed through the slits 17 and has the ends exposed on the outside of the waist band to receive fastening members 20 so that the end of this elastic webbing may be adjustably connected to any of the eyelets 21 secured in the web- 95 bing 11 and the lining 18. The fastening members 20 comprise metallic clips folded to grip the opposite sides of the elastic web- 100 bing 19 and from the ends of one of the folded portions are the stems 22 which pre- 105 sent a fastener of greater length than the slits 17 so that the fastener cannot accidentally pass through the slits 17. This side of the clamp is also recessed to form a tongue 23 which is bent to have locking en- gagement with any of the eyelets 21 and the 110 opposite folded portion of the clamp is formed into a series of teeth 24 which have

their ends embedded in the elastic webbing 19 to securely hold the fastener to the webbing.

It is evident from the foregoing that 5 with this type of waist band secured in a garment, desired binding action may be established by adjustment of the elastic webbing 19 to create the desired tension and with this webbing passing through a pocket 10 formed by the webbing 11 and the garment, the gathered portion of the garment is kept in form.

It is evident that modifications can be made in view of the foregoing description 15 without departing from the spirit of the claims, and no limitation is implied by the drawing which is for illustrative purposes only.

Having thus described this invention I 20 claim:

1. In a waist band of the class described, non-elastic webbing, reinforcing material secured to said non-elastic webbing throughout sections thereof, said non-elastic webbing and reinforcing material having transverse slits formed therein, in spaced relation, eyelets secured in said non-elastic webbing and reinforcing material in spaced relation beyond the slit portions, an elastic 25 webbing having its ends passed through the slit portion of said non-elastic webbing, fasteners carried by the ends of the elastic webbing having extensions from the ends thereof to give these fasteners a length 30 greater than the slits in the non-elastic webbing, and hooks formed on said fasteners for coöperation with any of the eyelets carried by the non-elastic webbing.

2. In a waist band of the class described, 40 a non-elastic webbing having transverse slits formed therein in spaced relation, an elastic webbing having portions thereof passing through the slit portions of the non-elastic

webbing, and fasteners carried by the elastic webbing of a size greater than the slit portion to necessitate displacement of said fasteners from their normal position relative to the slit portions for passage through said slit portions.

3. In a waist band of the class described, 50 a non-elastic webbing having eyelets formed therein in spaced relation, an elastic webbing detachably carried by said non-elastic webbing, and fasteners carried by the end of said elastic webbing, said fasteners comprising folded members, having one of the folded portions formed in a plurality of teeth which are embedded into the elastic webbing, and having the other folded portion provided with extensions from the ends 55 thereof and with a hook member centrally formed therein.

4. In a waist band of the class described, a non-elastic binding for attachment into the waist band of a garment, having transverse slits formed therein in spaced relation between the ends of said band, a plurality of eyelets carried by said band between the slit portions and the ends of the band, an elastic web carried by said band passing 70 through the slit portions of said band, and fastening members carried by the end of said elastic webbing for engagement with one or another of the eyelets toward the end of the band, said fasteners having extensions from 75 the ends thereof to present a greater dimension of said fasteners than the longitudinal dimension of the slit portion to prevent accidental displacement of the ends of the elastic webbing through said slit portion.

In testimony whereof I affix my signature in presence of two witnesses.

MILTON L. HELLER

In presence of—

W. M. MANN,

WILLIAM T. JONES.
